PROCESS OF MAKING SLIP LASTED SHOES

Filed May 18, 1944

INVENTOR:
JOHN J. WALSH,
BY *Alfred W. Pechelt*
ATTORNEY.

UNITED STATES PATENT OFFICE

2,406,975

PROCESS OF MAKING SLIP LASTED SHOES

John J. Walsh, Des Peres, Mo., assignor to Penaljo Company, St. Louis, Mo., a firm

Application May 18, 1944, Serial No. 536,069

3 Claims. (Cl. 12—142)

1

This invention relates to a new and useful improvement in the process of making shoes.

My invention has for its primary object the provision of a shoe requiring for its production only a few process operations not only for the most part of so-called slip-last type, but also readily effected with ease, accuracy, and precision by relatively unskilled workers and with consequent savings in labor costs and the elimination of losses by reason of faulty and rejected shoes.

My invention has for a further object the provision of a shoe through and by the employment of the process-operations mentioned which is simple and sturdy in structure, which is soft and comfortable on the foot, which is light in weight and attractive in appearance, and which is efficiently serviceable.

And with the above and other objects in view, my invention resides in the novel features of form, construction, arrangement, and combination of parts and in the unique steps or process of shoe production all presently described and pointed out in the claims.

In the accompanying drawing,

Figures 1 to 6, both inclusive, illustrate in plan or perspective some of the elements, namely, the insole, the upper, and strap members employed in the construction of a shoe in accordance with my present invention;

Figures 7 and 8 are side elevational and bottom plan views, respectively, of the shoe in position on a slip last;

Figure 9 is a bottom plan view, partly broken away, of the shoe after application thereto of a sole member;

Figure 10 is a side elevational view of the completed shoe;

Figure 11 is a transverse sectional view of the completed shoe taken approximately along the line 11—11 of Figure 10;

Figure 12 is a fragmentary longitudinal sectional view of the completed shoe taken approximately along the line 12—12 of Figure 11;

Figures 13 and 14 are views, respectively, of a modified form of upper member and insole member designed to be assembled therewith for the manufacture of a shoe of the so-called pump type.

Referring now more in detail and by reference characters to the drawing, which is illustrative both of practical embodiments of a shoe of my present invention and of its method or process of manufacture or production, the present shoe is built up on an edge-bound insole as a founda-

2

tion without the employment or use of a last during the initial stages of its manufacture.

To such end, I provide a section or piece 1 of cloth, thin leather, or other flexible fabric or material cut to and having the general outline or contour and dimensions of the outer sole of the particular shoe being manufactured, as best seen in Figure 1.

A suitable strip of leather, fabric, or binding tape 2 is then stitched around the entire margin of the section 1 in the formation of an edge-bound insole A. The insole A is then placed beneath a suitable pattern (not shown) and, with crayon or marking pencil, pairs of guide marks, a, a, b, b, and c, c, are inscribed thereon, as shown in Figure 3.

The vamp member B, Figure 4, is first cut and otherwise constructed to approximately conform to the contour, shape, and size required in the finished shoe. Such vamp B may, of course, be made of any suitable leather, fabric, or other material customarily employed in shoe manufacture and may, as illustrated in the present instance, be of the open toe type, although it will be understood that a closed toe type of shoe may equally well be constructed by this present method. After being cut and stitched, the vamp member B is placed under a suitable pattern (not shown) and, with a marking pencil or crayon, is inscribed on the outsole contacting face with pairs of guide marks d, d, and e, e, as shown in Figure 4, positioned for registration, respectively, with the guide marks a, a, and b, b, of the insole A. In addition, a heel strap assembly C is formed, as shown in Figure 5, consisting of a back-strap 3 and a pair of buckle-connected ankle straps 4, 4', the back-strap 3 being also provided with guide marks f, f, for registration with the guide marks c, c, of the insole A.

As an initial assembly step, the vamp member B is marginally folded over the insole A so that the respective guide marks come into registration and then secured by short lines of stitches 5, 6, as shown in Figure 6. Similarly, the back-strap 3 is folded over so that the guide marks f, f, are in registration with the guide marks c, c, and secured by lines of stitches 7, also as shown in Figure 6.

With the parts A, B, and C so joined or united one to the other, the shoe is then placed on a last L, and in order to insure subsequent precise lasting, tacks or other temporary securing members 8 are preferably disposed through the insole A and into the last L, as indicated in Figures 7 and 8. The unsecured margins of the vamp B are then

suitably coated with adhesive and then "pulled over" and pressed flatwise upon the corresponding marginal portion of the insole A.

When the "pulled over" margins of the vamp B have "set," the temporary securing tacks 8 are removed and an outer sole D of the desired shoe-contour, design, and shape is then adhesively or otherwise suitably fixed flatwise to and upon the under face of the insole A and over, and thereby concealing, the underfolded marginal portions of the insole A and upper B, as is best seen in Figures 9 and 10. Finally the shoe is completed by adhesively securing therein a conventional sock-lining E, and in due course a heel F is suitably affixed at the desired location to and upon the under face of the outer sole D, as illustrated in Figure 10.

If desired, a one-piece upper B' of the "open toe-and-heel" type, as shown in Figure 13, may be employed. In such case, the upper B' will be provided with guide marks d', d', e', e', and an insole member A' substantially similar to the previously described insole member A will be employed, except that only two pairs of guide marks a', a', and b', b', will be necessary, as shown in Figure 14. This modified form of shoe will of course be assembled exactly in the manner previously described.

It should be noted that the present method makes possible the manufacture of an extremely efficient shoe by relatively unskilled workmen inasmuch as the assembly operations prior to placing the shoe on a last are facilitated by the use of the several pairs of guide marks. A relatively untrained workman can easily superimpose the guide marks of the insole A and the vamp member B and secure the two parts together in such position, so that the size of the finished shoe will be accurate. Furthermore, with the parts stitched together along the lines of registration of the guide marks, there is no danger that the shoe will accidentally come apart due to unskilled handling while it is being placed upon the last L. In addition, the finished shoe retains its size and shape and is much more durable by reason of permanent securement in limited areas or regions by lines of stitches as above described. This results from the fact that the lines of stitches are extremely strong and flexible and, by being placed adjacent the initial points of juncture between the insole and vamp member at the toe and shank, will take much greater shear stresses and will effectively overcome the tendency for the outer edges of the cemented seams to peel away, as is ordinarily encountered in cemented shoes.

It will be understood, of course, that the shoe-parts or elements are permitted to stand from time to time during the production of the shoe to allow the adhesive or cementitious binding or securing material to dry and harden, and it will also be understood that other changes and modifications in the form, construction, arrangement, and combination of the several parts of the shoe, as well as changes also in its steps of manufacture or production, may be made and substituted for those herein shown and described without de-

parting from the nature and principle of my invention.

Having thus described my invention, what I claim and desire to secure by Letters Patent is:

- 5 1. That process of making slip-lasted shoes which includes forming an insole having approximately the contour of the finished shoe, forming an upper also having the approximate dimensions and shape corresponding to those of the finished shoe and being adapted to be ultimately secured to opposite sides of the insole along continuous lines between the toe and shank of the shoe, folding the upper marginally over and upon the under face of the insole, initially stitching said upper to the insole prior to lasting and only in limited areas adjacent the toe and shank portions of the insole while leaving the margins of the upper free between such limited areas of securement, placing the partially completed shoe upon a last and thereupon pulling over and cementing down the unstitched margins of the upper and applying a sole member.
- 10 2. In a process of making slip-lasted shoes, the steps of providing an insole having approximately the contour of the finished shoe, placing a pair of guide marks on opposite sides of the toe portion of the insole, placing a pair of guide marks on opposite sides of the shank portion of the insole, providing an upper also having the approximate dimensions and shape corresponding to those of the finished shoe, placing pairs of guide marks on the upper in suitable positions for registration respectively with the guide marks of the insole when the shoe is assembled, folding the upper marginally over the insole so that the respective guide marks are in visible alignment, permanently securing the upper and insole together in the region of the registered guide marks prior to lasting, lasting and adhesively securing the margins of the upper to the insole intermediate the points of permanent securement, and then applying a sole member to the bottom of the shoe.
- 15 3. In a process of shoe production, the steps of providing an insole having approximately the contour of the finished shoe, placing a pair of guide marks on opposite sides of the toe portion of the insole, placing a pair of guide marks on opposite sides of the shank portion of the insole, providing an upper also having the approximate dimensions and shape corresponding to those of the finished shoe, placing pairs of guide marks on the upper in suitable positions for registration respectively with the guide marks of the insole when the shoe is assembled, folding the upper marginally over the insole so that the respective guide marks are in visible alignment, permanently securing the upper and insole together in the region of the registered guide marks prior to lasting, placing the thusly secured upper and insole upon a last, lasting and adhesively securing the margins of the upper to the insole intermediate the points of permanent securement, and then applying a sole member to the bottom of the shoe.
